ABSTRACT

In a cut-off device for a continuous rod making machine, in which the rod is supported during cutting by a reciprocating ledger, the cut is timed so that it takes place either completely before or completely after the ledger reaches its peak velocity.

CUT-OFF DEVICES FOR CONTINUOUS ROD-MAKING MACHINES

Continuous-rod making machines such as cigarette making machines and cigarette filter rod making machines commonly include a cut-off device which cuts a continuous rod into short lengths. Such cut-off devices commonly include a ledger which supports the rod during cutting and has a reciprocating motion produced by a crank. Thus the velocity of the ledge varies approximately sinusoidally, whereas the continuous rod travels at a uniform speed.

It has hitherto been the practice to arrange that the cutting action is symmetrically timed in relation to the velocity peak of the ledger. That is to say, the starting and finishing points of the cutting operation occurred approximately at the same intervals in time before and after the ledger attained its peak velocity. The maximum velocity difference between the rod and the ledger was thereby kept as small as possible.

According to the present invention the timing of the knife in relation to the ledger is so arranged that the points in time at which each cutting operation commences and finishes are both either before or are both after the point in time at which the ledger reaches its peak velocity.

It has been found especially at high speeds, for example when making about 4,000 cigarettes per minute, that if the velocity peak of the ledger occurs during cutting backlash in the ledger drive can spoil the cut. This is because the acceleration of the ledger reverses at the peak velocity point, so that backlash allows the ledger to make an abrupt and undesirable movement relative to the rod. By arranging that cutting is completely carried out before or after the velocity peak, this backlash effect is avoided. Moreover this enables the clearance to be reduced between the guide tubes between which the knife passes to perform each cut.

The knife is preferably one with a part-helical blade, for example as shown in U.S. Pat. No. 3,604,162. The ledger may for example be as shown in U.S. Pat. No. 3,241,414.

Preferably cutting takes place during a part of the ledger stroke which includes a nodal point; that is to say a point in time at which the ledger speed equals rod speed. Furthermore in a preferred arrangement the relative displacement between the rod and the ledger before the nodal point is substantially equal to the relative displacement after the nodal point. This will be explained with reference to the accompanying drawings. In these drawings:

FIG. 1 is a diagrammatic representation of a ledger; and

FIG. 2 is a graph of ledger speed against ledger crank angle.

Referring to FIG. 1, a continuous rod 10, formed by a continuous rod making machine travels at uniform speed in the direction of the arrow. A ledger (shown diagrammatically) includes two guide tubes 12 and 13 carried by a body 14. A crank 15 drives a connecting rod 16 which is pivoted to the block 14 by a pin 17. The body 14 is carried by parallel rigid support arms 18 and 19. These arms are pivotally connected to the body 14 at 20 and 21 respectively, and to a frame at 22 and 23 respectively. The pivotal connections may, for example,

be crossed spring connections as described and shown in the aforementioned U.S. Pat. No. 3,241,414. Thus, rotation of the crank 15 causes the ledger body 14 to reciprocate with approximately a sinusoidal velocity. The crank 15 is driven by a driving means represented diagrammatically at 24 in FIG. 1.

Also linked to the driving means 24 is a cutter 25 for cutting the continuous rod 10 into the shorter lengths seen on the left hand side of FIG. 1.

The cutter 25 and the crank 15 are connected to the common driving means 24 so that the cutter 25 passes between the ledger tubes 12 and 13 and cuts the continuous rod before the ledger body reaches its peak velocity. Alternatively, the relative phases of the cutter 25 and crank 15 may be such that the cut takes place in a part of the ledger stroke after the ledger has passed its peak velocity.

This invention can be more readily explained with reference to FIG. 2, which is a graph plotting mainly

the ledger speed (i.e. the speed of the ledger body 14 in FIG. 1) against crank angle. The curve C1 shows the ledger speed characteristic for a rod speed S as used in the past. The cutting started at a point A1 and finished at a point A2, these points being at equal distances from the point A3 which is where the ledger velocity is at a peak. It will be noted that the difference between the rod speed and the ledger speed was never very great, being represented by the distance V1 at the beginning and end of the cycle and by the distance V2 (which could be equal to V1) at the mid-point of the cycle.

The curve C2 shows the ledger speed characteristic adopted now according to the present invention for use in a rod which still moves at the same speed S. The peak velocity is higher, being produced by an increase in the radius of the crank. Cutting now starts at the point A4 and finishes at the point A5.

The ledger velocity curve is such that the relative displacements between the rod and the ledger before and after the nodal point N are approximately equal. That is to say, the area D1 on the graph, bounded by the curve C2, the horizontal line at S and the vertical line at A4, is equal to the area D2 bounded by the curve C2, the horizontal line at S and the vertical line at A5. Thus the displacements on opposite sides of the nodal points cancel out one another.

There is now a bigger difference between the rod velocity and the ledger velocity at the beginning of the cut (and also at the end of the cut, though the difference here is less), but this can be tolerated as the effect is still small compared with the abrupt relative movement which occurred hitherto as a result of backlash.

What I claim as my invention and desire to secure by Letters Patent is:

1. A cigarette or other continuous rod making machine having a cut-off device for cutting a moving continuous rod into predetermined lengths, comprising a ledger which supports the rod during cutting and which is driven in a reciprocatory manner, including an acceleration mode and a deceleration mode during each stroke in the direction of movement of the rod, and a knife for cutting the rod, arranged so that the knife both starts and completes the cut during one of the said modes.

2. A machine according to claim 1 in which the ledger is driven by a crank so that it reciprocates with an approximately sinusoidal velocity.

3. A machine according to claim 1 arranged to cut during a part of each ledger stroke which includes a nodal point.

4. A machine according to claim 3 in which the relative displacement between the rod and the ledger before the nodal point is substantially equal to the relative displacement after the nodal point.

5. A method of cutting a continuous lengthwise moving rod into rod sections of predetermined length, comprising supporting the rod by means of a rod supporting means, driving the rod supporting means in a reciprocatory manner, including an acceleration mode and a deceleration mode during each stroke of the rod supporting means while moving in the direction of motion of the rod, and cutting the continuous rod entirely during one of the said modes.

6. A method according to claim 5 in which a nodal point of the speed of the rod supporting means in relation to the rod speed occurs during cutting.

7. A method according to claim 6 in which the relative displacement between the rod and the rod supporting means before the nodal point is substantially equal

to the relative displacement after the nodal point.

8. A method according to claim 5 in which the continuous rod is a continuous cigarette rod.

9. A cigarette or other continuous rod making machine having a cut-off device for cutting a continuous lengthwise moving rod into rod sections of predetermined length, comprising a reciprocating ledger to support the rod during cutting; a cutting means for cutting the rod; and drive means for driving

10 the ledger and the cutting means; the driving means being connected to the ledger by a crank so as to drive the ledger with a substantially sinusoidal velocity having an acceleration mode and a deceleration mode during each stroke of the ledger in the direction of motion 15 of the rod, and the driving means being connected to the cutting means so that the cutting means both starts and completes each cut during one of the said modes.

10. A machine according to claim 9 arranged to cut during a part of said mode which includes a nodal point.

11. A machine according to claim 10 in which the relative displacement between the rod and the ledger before the nodal point is substantially equal to the relative displacement after the nodal point.
